UNITED STATES PATENT OFFICE.

NIELS PETER PETERSEN, OF ALHAMBRA, CALIFORNIA.

DESIGN FOR A SUPPORT FOR A FLAGSTAFF TABLE DECORATION.

60,295.

Specification for Design.

Patented Jan. 24, 1922.

Application filed July 12, 1921. Serial No. 484,213. Term of patent 7 years.

To all whom it may concern:

Be it known that I, NIELS PETER PETERSEN, a citizen of the United States, residing at Alhambra, in the county of Los Angeles and State of California, have invented a new, original, and ornamental Design for a Support for a Flagstaff Table Decoration, of which the following is a specification, reference being had to the accompanying drawing, forming a part thereof.

Figure 1 is a side elevation of a support for a flagstaff table decoration showing my new design.

Fig. 2 is a plan of the support shown in Fig. 1.

The hexagonal center post is supported by the legs extending outwardly from the lower end of said center post.

I claim:

The ornamental design for a support for a flagstaff table decoration as shown.

Signed at Los Angeles, in the county of Los Angeles, and State of California, this 1st day of July, 1921.

NIELS PETER PETERSEN.
